UNITED STATES PATENT OFFICE

JOHN C. BLACK, OF LOS ANGELES, CALIFORNIA, ASSIGNOR TO GASOLINE PRODUCTS COMPANY, INC., OF NEWARK, NEW JERSEY, A CORPORATION OF DELAWARE

LINER FOR CRACKING APPARATUS

Application filed March 23, 1927. Serial No. 177,732.

This invention relates to an improvement in pipe coils in which a high temperature, high pressure, or a high speed of flow of the oil, or a combination of any of these conditions, is to be expected, the said coils being used in some such heater as that employed in converting high boiling point hydrocarbon oils into low boiling point hydrocarbon oils, i. e. the process of cracking. The said improvement is effected by the use of a liner at the points in the said pipe coils where the flow of the liquid changes in direction.

This apparatus is particularly adaptable in all forms of cracking apparatus for the production of low boiling hydrocarbons from high boiling hydrocarbons and may be employed successfully in my process as described in United States Patent No. 1,421,772, patented October 10, 1922, to which reference is hereby made.

I have found that there is an excessive diminution of the metal in the tubes in a cracking coil where the temperatures are substantially above 600° F. at the points where the direction of flow of the oil in the tubes is changed, which I believe is due to erosion of the metal by the carbon particles from the decomposition of the hydrocarbons, or it may be due to a combination of corrosion and erosion, the former being caused by the combination of the steel of the tube and the sulphur contained in the cracking hydrocarbons.

We have found that erosion and corrosion of the tubes do not occur beyond approximately six or eight inches from the return bend. This is due apparently to the flow being stream lined beyond these distances, whereas where highly turbulent action occurs in the return bends, the corrosion and erosion are excessive, and for this reason I have found that the liner should extend into the run of the pipe for approximately six or eight inches, or to a point where stream lined flow occurs. This is an important feature as it obviates the necessity of lining the whole tube from end to end.

It is an object of the present invention to minimize this corrosion and erosion by placing a particularly non-corrosive and non-

erosive metal at the points where corrosion and erosion are most likely to occur.

It is an object of the present invention to provide an economical and useful manner in which to repair the tubes where and when said corrosion and erosion do occur.

We attain these objects by placing liners of metal plated with chromium or tungsten, or liners of alloys of the same, or in certain cases we may use a liner composed of steel only, which may be replaced easily, inside the tubes at certain points, as will be understood better by reference to the accompanying drawings.

Figure 1 is an end view of a typical pair of pipes showing a cross-over pipe from one to the other.

Figure 2 is a section of Figure 1 taken along the center line 2—2.

Figure 3 is an end view of a typical plug used in each end of each pipe in the coil.

Figure 4 is a side view of said plug.

Fig. 5 shows a side elevation of a pipe coil.

Figure 6 is a plan view of a template to be explained later.

Figure 7 is a plan view of a template to be explained later.

In Figure 5 the direction of flow of the liquid is indicated by a series of arrows. A pipe 2 is joined to a pipe 7 by a cross-over pipe 4. Inside the cross-over end of pipe 2 is placed a liner 1 of said metals or alloys. A plug 3 is screwed into the end of pipe 2. Inside the cross-over 4 is a liner 5 of said metals or alloys. The cross-over 4 is joined to the pipe 7, inside of which is placed a liner 6 of said metals or alloys, the end of the pipe 7 being closed by a plug.

The above arrangement is typical of all cross-overs.

In Figure 2 the pipe 8 has welded to it a piece of pipe 2 of similar outside diameter but of a greater inside diameter. The liner 1 is a push-fit inside the pipe 2 and the inside diameter of the liner 1 is the same as that of the pipe 8 thus obviating any obstruction to the flow of liquid. The pipes 9 and 7 and the liner 6 are constructed in a similar manner. The plug 3 is screwed into the ends of 100

pipe 2 or 7 and has welded to its inside face a plate 10 of said metals. The pipes 8 and 9 are then placed in their positions relative to each other and the cross-over liner 5 is tack welded to the pipe liners 1 and 6 at the points 5 12. It is not essential that the lining sections should be a tight fit when first placed in the tubes as the foreign bodies in the liquid will soon fill up any cracks and will cement the 10 liners in place and the liners will become practically integral with the tubes. The foreign bodies so deposited will remain in place and will not be removed by the ordinary process used in purging.

15 The cross-over pipe 4 is cut into halves and is then placed around the cross-over liner 5 and welded in position, the cuts which have the cross-over being welded also.

Figure 6 shows the template 15 from which 20 the liners 1 and 6 will be cut from a flat plate of said metals and rolled into a tube of the necessary diameter.

Figure 7 shows the template 14 from which 25 the cross-over liner 5 will be cut from a flat plate of said metals and rolled to a tube of the necessary diameter.

Having thus described the nature of said invention and the best means I know for carrying the same into practical effect, I 30 claim:

1. An apparatus for the prevention of erosion on the inside of pipe coils, the coils comprising pairs of pipe sections, each pair having a cross-over near one end, said ends having 35 internal bores of greater diameter than the intermediate pipe sections, push-in liners for said ends for reducing the bores of the ends to conform in diameter to the bores of the intermediate sections said cross-overs connecting said ends, and having linings interfitting the linings of said ends.

2. A pipe coil for cracking hydrocarbon under high pressure and heat, comprising a coil made up of pairs of sections of pipes, each 45 pipe having an end welded to an intermediate section, said end being of larger bore than the intermediate section and a push-fit liner in said end adapted to reduce the bore of the end to the bore of the intermediate section.

50 3. A hydrocarbon heating element comprising a plurality of pipe lengths having removable plugs in both ends of each pipe length and alternating cross-overs between the pipe lengths, chromium alloy metal liners inserted 55 on the inside of each cross-over, attached to the inward faces of said plugs, and pushed into the inside of each end of each pipe length respectively and extending into the pipes for a distance to protect the ends of said pipes, 60 cross-overs and plugs from the effect of corrosion.

4. In combination with a hydrocarbon heating element, a plurality of assembled pipe lengths, connecting cross-overs and plugs, 65 metal liners of non-erosive metal made from

a blank sheet and disposed in said cross-overs and metal liners attached to the inward faces of said plugs to protect the plugs and cross-overs from the effect of corrosion.

5. A pipe section for conducting erosives 70 through it, comprising an end and an intermediate section, the intermediate section having a smaller bore than the end section, a push-in lining with an opening in its side for the inner bore of the end section and resting against the end of the said smaller bore portion and a screw plug with its end resting against the outer end of said lining.

6. A hydrocarbon heating element assembly 80 having a plurality of pipe lengths with alternating cross-overs connecting the pipe lengths, liners of relatively non-corrosive metal disposed on the inside of said cross-overs, liners slipped into the end of said pipe lengths and extending for a short distance 85 beyond the cross-overs to protect these portions of said element from corrosion.

7. A pipe coil comprising successive pairs of sections, a cross-over in each pair near the 90 end of the section, said ends having linings consisting of an erosion resisting metal blank bent to tube form and with cut out portion on either sides thereof and inserted in said end as a lining therefor, said cross-over portion having therein a lining with its ends 95 coinciding with the edges of the cut out portion of said metal blank.

8. In combination with a hydrocarbon heating element assembly including pipe lengths, cross-overs and plugs, metal liners 100 of relatively non-corrosive material pushed into the inside of each end of each pipe length, cross-overs having liners inserted therein and liners on the inward faces of said plugs to protect the plugs, pipe lengths and cross-overs from the effect of corrosion.

9. A heating coil comprising successive pairs of metal lined pipe sections and cross-overs between each pair near one end, said 110 ends being welded to the intermediate pipe sections and the cross-overs welded to said ends whereby push-in linings may be inserted in said cross-overs and ends before the ends are welded to the intermediate section and the cross-overs to said ends.

10. In combination with a hydrocarbon heating element assembly, including cross-overs and pipe lengths with removable plugs, metal liners of relatively non-corrosive material having a push fit into the inside of each end of each pipe length and cross-over, and extending into the pipes of each end of said pipe lengths for a distance to protect the ends of said pipe lengths and cross-overs from the effect of corrosion.

11. A heating coil made up of successive pairs of pipe and a cross-over in each pair near the ends, the ends of the pipe having bores of larger diameter than the intermediate sections, a slip-in erosion resisting liner 130

in the ends extending on either side of the cross-overs and a plug abutting the lining in each end.

12. A heating coil made up of successive 5 pairs of pipe and a cross-over for each pair at the ends, the ends of the pipe having bores of larger diameter than the intermediate portions and slip-in erosion resisting liners in the ends thereof and within the enlarged 10 bores.

13. A heating coil comprising a plurality 15 of pairs of tubes, a crossover for each pair and corrosive resistant means positioned in the ends of each tube forming a continuous unobstructed surface at the juncture of said means with the tube.

14. A heating coil comprising a plurality 20 of pairs of tubes, a crossover for each pair and a slip-in non-corrosive liner in the ends of each tube forming a continuous unobstructed surface at the juncture of the liner with the tube.

15. A heating coil comprising a plurality 25 of pairs of tubes, crossover for each pair, a slip-in non-corrosive liner in the ends of each tube forming a continuous unobstructed surface of the juncture of the liner with the tube and a non-corrosive liner extending throughout the interior of said crossover.

30 In testimony whereof I affix my signature.
JOHN C. BLACK.
